METHOD AND APPARATUS FOR PRODUCING
MOTOR FUELPercy A. Maschwitz, Toledo, Ohio, assignor to
The Pure Oil Company, Chicago, Ill., a corpora-
tion of Ohio

Application August 13, 1936, Serial No. 95,745

12 Claims. (Cl. 196—9)

This invention relates to method and apparatus for producing high yields of high octane motor fuel from crude oil. More particularly the invention resides in the combination of cracking, reforming, and polymerizing in such manner that crude oil may be subjected to a continuous process in which the cracking stock, naphtha, and gases are treated simultaneously in a unitary process to convert them into motor fuel.

0 In accordance with the invention, crude oil may be topped in the usual manner to remove the gasoline, naphtha, and/or kerosene. The total overhead cut may be reformed at elevated temperatures and pressures or only the heavier fraction thereof may be reformed. The topped crude may be subjected to any suitable cracking operation in liquid, liquid-vapor, or vapor phase, and the resulting gasoline distillate combined with the products from the reforming operation. 10 The combined products may be clay treated and fractionated to end point gasoline. The heavy ends separated from the mixture may be recycled to the cracking unit.

The gases from the cracking and reforming operation may be intimately contacted with a portion or all the overhead fraction to be reformed under elevated pressure in order to dissolve a portion of the gases. The naphtha enriched with the heavier gas fractions may be subjected to reforming, and the unabsorbed gases may be subjected to suitable conversion in a separate still. The distillate produced in the gas conversion step may be combined with the cracked distillate and the reformed naphtha. 15 The gas resulting from the gas conversion may be fractionated by absorption to remove hydrogen, methane and other light gases, and the absorbed constituents separated from the absorbent and recycled to the gas conversion zone. A composite distillate of cracked gasoline, reformed naphtha, and polymerized condensate is formed having an unusually high octane rating. The yield of gasoline is also higher than has heretofore been obtained for gasoline of equivalent knock rating.

The invention may be more clearly understood from the following detailed description considered in connection with the accompanying drawings, of which,

10 Figure 1 is a diagrammatic elevational view of apparatus forming part of the invention and in which the method may be carried out.

Figure 2 is a diagrammatic view of conventional apparatus for topping and cracking crude oil.

Referring to the drawings, naphtha, gasoline, or kerosene may be charged through line 1 by means of pump 3 either directly into the heating and reforming coil 5 located in furnace 6, or through the line 7 controlled by valve 9. The naphtha, etc. may be obtained directly from a topping unit used in conjunction with the oil cracking process, or may be obtained from a separate source. If desired, the charging stock may be split into two streams by proper regulation of the valve 9 in line 7 and the valve 11 in line 1. From the line 7 the charging stock, which is preferably heavy naphtha, passes into the top of an absorption tower 13 where it passes in countercurrent contact with a stream of gases fed to the lower portion of the absorber through the line 15. The gases fed through line 15 may contain unsaturated hydrocarbons ranging in amount from 20—55%. The absorption tower is preferably operated at a pressure of from 150—200 20 pounds per square inch and at a temperature of 100° F. or less.

Rich oil is withdrawn from the bottom of the absorption tower 13 through line 17 by means of pump 19 and is charged through line 1 into the heating and reforming coil 5. The oil thus charged to the coil 5 will have dissolved therein the heavier constituents of the gas, such as butane, butylene and some propane and propylene. The rich oil may be subjected to pressures of 30 500—3000 pounds per square inch and to temperatures ranging from 800°—1200° F. in the coil 5.

The products leaving the reforming coil 5 pass into arrester 21 where they are contacted with cool oil withdrawn from the gas separator 23 through line 25 by means of pump 27. The reaction products are chilled in the arrester 21 to a temperature below 700° F. and preferably to a temperature between 500° and 600° F. The partially cooled reaction products pass through line 29 controlled by valve 30 to the upper portion of a chamber 31 containing a bed of fuller's earth or other clay capable of functioning as an adsorptive catalyst. The clay chamber may be maintained under substantially reaction pressure 40 or the pressure may be reduced somewhat by means of the valve 30 before the products enter the clay chamber. In the clay chamber the unstable gum-forming and color-imparting bodies undergo polymerization to heavier bodies. The combined reaction products are withdrawn from the bottom of the clay chamber through line 33 controlled by valve 35 and pass into the lower portion of fractionating tower 37. The pressure 45 on the products may be reduced to approxi-

50

mately 150-200 pounds per square inch or lower before entering the fractionating tower. If necessary, the products leaving the clay chamber may be preheated prior to passing into the fractionating tower. In the fractionating tower 37, vaporization of the lighter vapors boiling within the gasoline range takes place, and these vapors pass overhead through line 39 while the heavier ends and polymers formed in the clay chamber 5 and 10 and in the reforming coil 5, may be withdrawn through the line 41 controlled by valve 43. Open steam may be used in tower 37 and in subsequent fractionating towers to assist in separating light ends from the unvaporized portions. When open 15 steam is used, suitable provision should be made for drawing off water from the separators following the fractionating towers. The higher boiling materials withdrawn through line 41 may be recycled to an oil cracking unit, such as a 20 vapor phase unit, or may be withdrawn from the system. It is apparent that the heavy boiling liquid withdrawn through the line 41 may be in part withdrawn from the system and in part recycled to an oil cracking system.

25 The vapors and gases withdrawn through line 39 pass through the condenser 45 where the temperature of the products is lowered to approximately 100° F. or less and then through line 47 into accumulator 49. The condensate collected in 30 accumulator 49 may be in part withdrawn through line 51 by means of pump 53 and recycled to the upper portion of the fractionating tower 37 as reflux. The remaining portion of the condensate may be withdrawn from the bottom of the accumulator 49 through line 55 controlled by valve 57, into accumulator 59.

Uncondensed gases leave the top of the accumulator 49 through line 61, pass through cooler 63 where the temperature is further reduced, if necessary, to or below 100° F., and are then charged through line 67 into accumulator 59. Gas leaving the top of gas separator 23 through line 71 may be compressed by compressor 73 to a pressure of approximately 150-200 pounds per square inch and charged into accumulator 59 together with the gases from accumulator 49. The gases from the gas separator 23 may result from the cracking of topped crude or other oil in a cracking process, of the liquid, liquid-vapor, or vapor phase type. The combined gases and gasoline distillate from the cracking unit may pass through line 75, after having been cooled to a temperature sufficient to condense the vapors boiling within the gasoline range, into the gas separator 23 where the gas separates from the condensate.

Uncondensed gases leave the top of the accumulator 59 through line 77 and, after being cooled if necessary by passing through a cooler 60 (not shown), pass into the lower portion of the absorber 13 through the line 15. Any liquids condensed in accumulator 59 may be withdrawn therefrom through line 79 by means of pump 81 and charged into the upper portion of a stabilizer 65 83. The stabilizer is preferably maintained under a pressure of from 175-225 pounds per square inch. The stabilizer is equipped with bubble plates in order to secure fractionation. Unvaporized products may be withdrawn from the lower 70 portion of the stabilizer through line 85 and passed into reboiler 87 where they are heated to a temperature sufficient to vaporize those constituents such as propylene, butylene, propane and butane, which are undesirable in gasoline. These vapors and gases return from the reboiler to the

stabilizer through line 89. The unvaporized portions are withdrawn from the reboiler through line 91 and may be charged to the storage tank 92 through line 93 controlled by valve 94, or may be withdrawn to separate storage through line 97 controlled by valve 99. Uncondensed gases leave the stabilizer 83 through line 101, pass through condenser 103 into accumulator 105. Any condensate which forms in the accumulator may be recycled through line 107 by means of pump 109 to the top of the stabilizer, as reflux. The uncondensed gases leave the top of the accumulator 105 through line 111, pass through cooler 113, where the temperature is reduced to 100° F. or less, and join the gases from line 77 passing into the absorber 13.

Unabsorbed gases leave the top of the absorber 13 through line 115 and are charged by means of compressor 117 to the heating coil 119 located in furnace 121. The gases may be heated to a temperature ranging from 800°-1400° F. in the coil 119 under pressures of from 100-3000 pounds per square inch. The pressure used will depend upon the temperature to which the gases are heated. At higher temperatures, the pressure will be correspondingly lower, while at lower temperatures, higher pressures will be used. The temperature to which the gases are heated will depend to a large extent on the olefinic content of the gases. With gases of less than about 30% olefinic content, it is preferable to use temperatures of 1200°-1400° F. in order to obtain substantial cracking together with polymerization. When the olefinic content of the gases exceeds approximately 30%, temperatures below 1200° F. are preferable. The 30 heated gases leave coil 119 through line 123 controlled by valve 125 and may be either passed through reaction zone 127 or may be by-passed around the reaction zone through line 129 controlled by valve 131. The reaction zone 127 may 40 take either the form of an enlarged coil or an enlarged reaction chamber preferably heat insulated. If the products are subjected to high pressure treatment, it may be desirable to use the reaction zone, but where high temperatures and 45 low pressures are used with consequent short reaction periods, it may be desirable to by-pass the reaction zone. The particular conditions of temperature and pressure and the period of reaction desired will determine whether or not the reaction zone will be utilized. The products leaving the reaction zone 127 or the heating coil 119, as the case may be, pass through line 133 controlled by valve 135 into the lower portion of evaporator 137. Immediately after leaving the reaction zone 50 or the heating coil, the products are quickly chilled to a temperature of 600° F. or lower by means of contact with cool oil withdrawn from gas separator 139 through line 141 by means of pump 143. A portion of the oil from the line 141 may be 60 charged into the upper portion of the evaporator 137 through line 145 controlled by valve 147 to act as reflux. The pressure of the products entering the evaporator is preferably reduced to approximately 175-225 pounds per square inch. 65 Tarry constituents are knocked out and withdrawn from the bottom of the evaporator through line 149 controlled by valve 151 and may be either recycled to the oil cracking step or withdrawn from the system. The remaining vapors and 70 gases pass over the top of the evaporator through line 153, condenser 155 and line 157, into accumulator 159.

Condensate may be withdrawn from the accumulator 159 through line 161 and charged to

the gas separator 139. Uncondensed gases from the accumulator 159 are withdrawn from the top thereof through line 162 controlled by valve 163 and may be charged through line 164 controlled by valve 165 to the lower portion of absorption tower 167. When the gas conversion system is operated under low pressure, it may be necessary to compress the gases leaving accumulator 159, by means of compressor 168, prior to delivery to the absorber. Absorption oil, which may be heavy naphtha, mineral seal or gas oil, may be charged into the upper portion of the absorber through line 169 and passed in countercurrent contact with the gases charged to the absorber through line 164. The unabsorbed gases leave the top of the absorber through line 171 controlled by valve 173 and may be withdrawn from the system. The rich absorber oil may be withdrawn from the bottom of the absorber through line 175, passed through heat exchanger 177, line 179 controlled by valve 180 and heater 181, into an intermediate portion of the still 183. The absorbed gases and light vapors are stripped from the absorber oil and pass off the top of the still through line 185, through condenser 187, into the gas separator 139 where the condensed vapors mix with the condensate from the accumulator 159. A part of the condensate from the separator 139 may be returned from the bottom thereof through line 189 by means of pump 191 to the top of the still 183, as reflux. As previously stated, a portion of this condensate may be used as chilling fluid for the products leaving the polymerization zone. The remaining condensate is withdrawn from separator 139 through line 193 and may either be charged by means of pump 194 to the gas separator 23 where it is combined with the cracked light distillate to undergo clay treatment and final fractionation, or may be withdrawn from the system through line 195 controlled by valve 197 and separately collected. Uncondensed gas may be taken off the top of separator 139 and recycled to the inlet of coil 119 through line 198.

The denuded absorber oil is withdrawn from the bottom of the still 183 by means of pump 184 through line 199, heat exchanger 177, where it gives up a portion of its heat to the rich oil, and then charged through line 169 and cooler 201 into the top of the absorber. Makeup oil may be added to the line 169 as required through line 203 controlled by valve 205. The absorber 167 is preferably maintained under a pressure of 175-225 pounds per square inch and at a temperature of approximately 100° F. or less. The still 183 and gas separator 139 are preferably maintained under pressure of 150-200 pounds per square inch, but may be maintained at lower pressures when polymerization is carried out at low pressures.

It will be apparent that instead of utilizing separate absorption and stripping means for the uncondensed gases from the accumulator 159, the uncondensed gases therefrom may be recycled in whole or in part to the absorber 13 through line 207 controlled by valve 209. In order to do this it merely is necessary to close valves 165 in line 164 and to open the valve 209 in line 207. When operating in this manner excess gas may be removed from the system through line 211 controlled by valve 213.

Referring to Figure 2, crude oil is pumped by means of pump 220 through line 222 into heating coil 224. In the coil 224 the oil is heated sufficiently to vaporize the oil but not to crack it.

From the heating coil the oil passes into the fractionating tower 226. Gasoline is withdrawn overhead as a vapor through line 228 and passed through condenser 230 into separator 232 from which it may be withdrawn through line 234 controlled by valve 236.

Heavy naphtha containing or not containing kerosene may be withdrawn from an intermediate portion of the fractionator 226 through line 238. Line 234 is connected to line 238 by line 240 controlled by valve 242 so that topped gasoline may be mixed with heavy naphtha if desired prior to charging the latter through line 1 to the reforming coil.

Cracking stock may be withdrawn from the lower portion of the tower through line 244 controlled by valve 246 and charged by means of pump 248 through heating and cracking coil 250. From the cracking coil the reaction products may pass into evaporator 252. The vapors pass overhead from the evaporator through line 254 controlled by valve 256 into fractionating tower 258. Gasoline and gases are taken overhead from the fractionating tower through line 260 controlled by valve 262 into cooling and condensing coil 264. From the coil 264 the mixed gases and gasoline pass through line 75 to separator 23.

From the foregoing description it will be seen that a system has been provided for treating crude oil whereby the oil may be first topped and the natural gasoline fraction obtained from the topping operation or a heavy fraction thereof reformed either alone or in conjunction with conversion of hydrocarbon gases obtained from the cracking and reforming steps. The system further provides for conversion of the lighter portions of the gases under any desired conditions in order to produce therefrom either aromatic hydrocarbons or other liquid hydrocarbons boiling within the gasoline range, and for clay treatment and fractionation of the combined gasoline boiling range products to produce a motor fuel of high anti-knock characteristics.

The process provides a flexible means for treating hydrocarbon gases to produce therefrom motor fuel hydrocarbons boiling within the gasoline range. By absorbing the heavier gas constituents in the naphtha which is to be reformed, the necessity for separate conversion of these gases is avoided and at the same time means is provided for charging these gases in the liquid state to a conversion zone. The light portions of the gases, which cannot be absorbed, can be polymerized separately under conditions which are suitable to the olefinic content thereof. Moreover, the character of liquid products which may be obtained from the light gases can be regulated at will by independent control of the temperatures and pressures to which they are subjected. If it is not desired to make preponderantly aromatic hydrocarbons, high pressure conditions and lower temperatures may be used and larger yields of liquid products thereby obtained. Where the primary object is to obtain aromatic hydrocarbons from the light gaseous portions, higher temperatures and lower pressures may be utilized.

By subjecting the heavier and higher olefinic gas fraction to conversion absorbed in naphtha, unusually high yields of gasoline of high anti-knock value can be obtained. Apparently polymerization and alkylation take place simultaneously so that saturated as well as unsaturated hydrocarbons take part in the reaction. The light unabsorbed fraction, on the other hand, is relatively lean in olefinic content and requires

more severe treatment than the absorbed gases. By adjusting the pressure and temperature conditions in absorber 13 in accordance with the composition of the gas fed to it, the gas can be fractionated to yield two fractions most suitable for the particular conditions of reaction to which they are subjected and increased yields thereby obtained.

Although a specific method of cracking, reforming and polymerizing has been shown and described, it is to be understood that the invention is not limited to the specific form shown and described, but covers broadly process and apparatus for combining the steps of cracking, reforming and gas polymerization in a unitary process. Furthermore, although the invention has been described as being applicable to treatment of crude oil, it is apparent that oil, naphtha, and gases from separate sources may be utilized.

20. What is claimed is:

1. The method for producing motor fuel which comprises contacting low octane naphtha with olefin-containing hydrocarbon gas under conditions of temperature and pressure to absorb heavier constituents of the gas, subjecting the enriched naphtha in a heating and reaction zone to conditions of temperature and pressure suitable for increasing the octane rating of the naphtha and for converting a portion of the absorbed gas to hydrocarbons boiling within the motor fuel range, conducting gas not absorbed by the naphtha to heating and reaction zones entirely separate from said first mentioned heating and reaction zone and subjecting it to temperatures and under pressures suitable for converting a portion thereof to hydrocarbons boiling within the gasoline range, separating the gasoline boiling constituents from the gas conversion operation from the gases, combining said constituents with the total products from the enriched naphtha conversion operation, and subjecting the combined products without prior fractionation to clay treatment followed by fractionation to produce finished motor fuel.

45. 2. Method in accordance with claim 1 in which the olefin-containing gas is produced in an oil cracking operation.

3. Method in accordance with claim 1 in which the naphtha is obtained from topping crude oil, and the olefin-containing gas is produced in the cracking of the topped crude.

4. Method in accordance with claim 1 in which the gasoline boiling constituents from the gas conversion operation are mixed with gasoline boiling constituents from an oil cracking operation, and the combined constituents are directly contacted with the products issuing from the gas-naphtha conversion step in order to reduce the temperature of said products below conversion temperature prior to the clay treating step.

5. A method for producing motor fuel from crude oil which comprises topping the crude oil, cracking the topped crude, separating and condensing gasoline distillate, separating gases from said distillate, contacting cool naphtha, separated in said topping step, with said gases under conditions of temperature and pressure to dissolve heavier constituents of said gas in said naphtha, subjecting the enriched naphtha to conditions of temperature and pressure suitable for reforming said naphtha and for converting a portion of the dissolved gas to hydrocarbons boiling within the gasoline range, subjecting undissolved gases to separate conditions of temperature and

pressure suitable for converting them to hydrocarbons boiling within the gasoline range, separating gasoline hydrocarbons resulting from the latter step from the heavier and lighter reaction products, combining said gasoline hydrocarbons with gasoline distillate from the cracking step, contacting the combined gasoline distillate with hot reaction products issuing from the reforming operation under conditions to chill said reaction products below conversion temperature, 10 contacting the total products from the chilling step with clay under conditions of temperature and pressure to de-gum and de-colorize them, and fractionating the clay treated products to produce finished motor fuel.

6. Method in accordance with claim 5 in which the gases resulting from the separate gas conversion step are in part recycled to said naphtha-gas contacting step.

7. Method in accordance with claim 5 in which the gases resulting from the naphtha reforming step are charged to the naphtha-gas contacting step.

8. Method in accordance with claim 5 in which liquid hydrocarbons heavier than gasoline, produced in the reforming and gas conversion operations, are recycled to the cracking unit.

9. The process of producing gasoline which comprises, subjecting low octane naphtha in a heating and reaction zone to conditions of temperature and pressure suitable for increasing the octane rating thereof, quenching the reaction products by means of cool liquid hydrocarbons to suddenly terminate the reaction, fractionating the quenched products into normally liquid and normally gaseous hydrocarbons, contacting the gaseous hydrocarbons in an absorption zone with naphtha to be reformed, charging the rich naphtha to said heating and reaction zone, charging unabsorbed gases to separate heating and reaction zones wherein said unabsorbed gases are subjected to suitable conditions of temperature and pressure to convert a substantial portion thereof to gasoline boiling hydrocarbons, separating the reaction products into gases, 45 gasoline boiling hydrocarbons and hydrocarbons boiling above the gasoline range, charging said last-mentioned gasoline boiling hydrocarbons to the outlet of the first-mentioned reactive zone as part of the quenching liquid, charging raw 50 cracked gasoline to the outlet of said first-mentioned reaction zone as another portion of the quenching liquid, mixing cracked gases with said gaseous hydrocarbons prior to charging the latter to the absorption zone, and eliminating reaction 55 gases from said separate heating and reaction zones from the system.

10. Apparatus of the character described comprising a heating and reaction coil, means for passing liquid to the inlet of said coil, means for charging liquid to the outlet of said coil, fractionating means connected to the outlet of said coil subsequent to said liquid charging means, means for withdrawing gases from the upper part of said fractionating means, an absorber, 65 means for charging said gases to the lower part of said absorber, means for charging liquid to the upper part of said absorber in contact with said gases, means for passing liquid from the lower part of said absorber to the inlet of said 70 reaction coil, means for passing gases from the upper part of said absorber to a second heating means, a reaction means connected to said heating means, a second fractionating means connected to said reaction means, means for pass-

ing liquid products from said second fractionating means to the outlet of the heating and reaction coil, and means for eliminating gases, separated in said second fractionating means, from the system.

11. Apparatus in accordance with claim 10 in which a clay tower is connected between the

means for charging liquid to the outlet of the coil, and the first fractionating means.

12. Apparatus in accordance with claim 10 including means for charging liquid to the reaction coil or to the absorber.

PERCY A. MASCHWITZ.
